(57) **CLAIM**

The ornamental design for a power tap with low voltage cordless capability, as shown and described.

DESCRIPTION

FIG. 1 is a front perspective view of a power tap with low voltage cordless capability showing our new design mounted in an operating environment and with its doors shown in a closed position;

FIG. 2 is another front perspective view of the power tap with low voltage cordless capability of FIG. 1, shown in the operating environment and with its doors shown in an open position;

FIG. 3 is a front perspective view of the power tap with low voltage cordless capability of FIG. 2;

FIG. 4 is a rear perspective view of the power tap with low voltage cordless capability of FIG. 2;

FIG. 5 is a front elevation of the power tap with low voltage cordless capability of FIG. 2;

FIG. 6 is a rear elevation of the power tap with low voltage cordless capability of FIG. 2;

FIG. 7 is a right side elevation of the power tap with low voltage cordless capability of FIG. 2;

FIG. 8 is a left side elevation of the power tap with low voltage cordless capability of FIG. 2;

FIG. 9 is a top plan view of the power tap with low voltage cordless capability of FIG. 2;

FIG. 10 is a front elevation of the power tap with low voltage cordless capability of FIG. 1;

FIG. 11 is a rear elevation of the power tap with low voltage cordless capability of FIG. 1;

FIG. 12 is a right side elevation of the power tap with low voltage cordless capability of FIG. 1;

FIG. 13 is a left side elevation of the power tap with low voltage cordless capability of FIG. 1;

FIG. 14 is a top plan view of the power tap with low voltage cordless capability of FIG. 1; and,

FIG. 15 is a rear perspective view of the power tap with low voltage cordless capability of FIG. 1.

The broken lines in the figures represent unclaimed environment only and form no part of the claimed design.

The ornamental design for a power tap with low voltage cordless capability, as shown and described.

DESCRIPTION

FIG. 1 is a front perspective view of a power tap with low voltage cordless capability showing our new design mounted in an operating environment and with its doors shown in a closed position;

FIG. 2 is another front perspective view of the power tap with low voltage cordless capability of FIG. 1, shown in the operating environment and with its doors shown in an open position;

FIG. 3 is a front perspective view of the power tap with low voltage cordless capability of FIG. 2;

FIG. 4 is a rear perspective view of the power tap with low voltage cordless capability of FIG. 2;

FIG. 5 is a front elevation of the power tap with low voltage cordless capability of FIG. 2;

FIG. 6 is a rear elevation of the power tap with low voltage cordless capability of FIG. 2;

FIG. 7 is a right side elevation of the power tap with low voltage cordless capability of FIG. 2;

FIG. 8 is a left side elevation of the power tap with low voltage cordless capability of FIG. 2;

FIG. 9 is a top plan view of the power tap with low voltage cordless capability of FIG. 2;

FIG. 10 is a front elevation of the power tap with low voltage cordless capability of FIG. 1;

FIG. 11 is a rear elevation of the power tap with low voltage cordless capability of FIG. 1;

FIG. 12 is a right side elevation of the power tap with low voltage cordless capability of FIG. 1;

FIG. 13 is a left side elevation of the power tap with low voltage cordless capability of FIG. 1;

FIG. 14 is a top plan view of the power tap with low voltage cordless capability of FIG. 1; and,

FIG. 15 is a rear perspective view of the power tap with low voltage cordless capability of FIG. 1.

The broken lines in the figures represent unclaimed environment only and form no part of the claimed design.
